UNITED STATES PATENT OFFICE.

BLAKE F. PICKERING, OF SALMON FALLS, NEW HAMPSHIRE.

DESIGN FOR A WRENCH.

SPECIFICATION forming part of Design No. 13,065, dated July 18, 1882.

Application filed May 13, 1882. Term of patent 7 years.

To all whom it may concern:

Be it known that I, B. F. PICKERING, a citizen of the United States, and a resident of Salmon Falls, in the county of Strafford and State of New Hampshire, have invented a new and valuable Improvement in Designs for Wrenches; and I do hereby declare that the following is a full, clear, and exact description of the same, reference being had to the annexed drawings, making a part of this specification, and to the letters and figures of reference marked thereon.

Figure 1 of the drawings is a representation of a side view of this invention. Fig. 2 is a perspective view.

This invention has relation to wrenches; and it consists in the novel form and configuration set forth.

The faces of the wrench are flat and parallel. A jaw-head is arranged at each end, and the shank between the jaw-heads is oblique. The jaw-heads are of similar form, but different in size. Each jaw-head *a* is bounded on the external sides by a curved convex edge, *b*, and a straight, or nearly straight, edge, *c*, the convex curved edge of one head being connected by the concave edge curve *d* of the shank to the straight, or nearly straight, edge of the opposite head. Each head is formed with a truncated

tapering jaw-notch, *e*, extending from the end inward, and having the inner edge of its outer jaw, *g*, serrated, as indicated at *h*. These serrated edges are formed on parallel, or nearly parallel, lines with each other and with the shorter and straighter edges *c* of the jaw-heads. The form is such that while the inner jaws, *k*, are nearly in line with each other the jaw-notches are widely out of line, their general direction being oblique to the central line of the shank *l*.

What I claim and desire to secure is—

The design of a flat double-headed wrench, formed with tapering jaw-notches *e* in its ends out of line with each other, and an oblique shank, *l*, having concave edges *d* respectively connecting the straight, or nearly straight, edge *c* of the inner jaw, *k*, of one head with the convex edge *b* of the outer jaw, *g*, of the other head, as shown and set forth.

In testimony that I claim the above I have hereunto subscribed my name in the presence of two witnesses.

BLAKE FRANK PICKERING.
